Des. 234,863
Patented Apr. 15, 1975

234,863

KALEIDOSCOPE

Judith Karelitz, 430 E. 86th St.,
New York, N.Y. 10028

Filed May 6, 1971, Ser. No. 141,083

Term of patent 14 years

Int. Cl. D21—01
U.S. Cl. D34—15 A

FIG. 12.

FIG. 13.

FIG. 14.

FIG. 15.

FIG. 16.

FIG. 17.

FIG. 18.

FIG. 19.

FIG. 20.

FIG. 22.

FIG. 23.

FIG. 24.

FIG. 25.

FIG. 26.

FIG. 27.

FIG. 28.

FIG. 29.

FIG. 1 is a perspective view of a kaleidoscope embodying my new design;

FIG. 2 is a side elevational view thereof;

FIG. 3 is an end view thereof looking from the left of FIG. 1;

FIG. 4 is an opposite end view thereof;

FIG. 5 is a view similar to FIG. 2 showing a modification thereof;

FIG. 6 is an end view looking from the left of FIG. 5;

FIG. 7 is an end view looking from the right of FIG. 5;

FIG. 8 is a view similar to FIGS. 2 and 5 showing another modification, the drawing being lined for color;

FIG. 9 is a view similar to FIG. 8 with a kaleidoscope rotated to show a different elevation;

FIG. 10 is an end view looking from the left of FIGS. 8 and 9;

FIG. 11 is an end view looking from the right of FIGS. 8 and 9;

FIG. 12 is a side elevational view of yet a further modification thereof;

FIG. 13 is an end view looking from the left of FIG. 12;

FIG. 14 is an end view looking from the right of FIG. 12;

FIG. 15 is a side elevational view of yet another modification thereof;

FIG. 16 is an end view looking from the left of FIG. 15;

FIG. 17 is an end view looking from the right of FIG. 15;

FIG. 18 is a side elevational view of still a further modification of my design;

FIG. 19 is an end view looking from the left of FIG. 18;

FIG. 20 is an end view looking from the right of FIG. 18;

FIG. 21 is a side elevational view of yet a further modification thereof;

FIG. 22 is an end view looking from the left of FIG. 21;

FIG. 23 is an end view looking from the right of FIG. 21;

FIG. 24 is a side elevational view of yet another modification thereof;

FIG. 25 is an end view looking from the left of FIG. 24;

FIG. 26 is an end view looking from the right of FIG. 24;

FIG. 27 is a side elevational view of still a further modification of my design;

FIG. 28 is an end view looking from the left of FIG. 27;

FIG. 29 is an end view looking from the right of FIG. 27.

I claim:

The ornamental design for a kaleidoscope, as shown and described.
